UNITED STATES PATENT OFFICE

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY

MARKING MACHINE

Application filed January 16, 1926. Serial No. 81,813.

This invention relates to marking machines and is illustrated as embodied in a marking machine provided with interchangeable individual types or markers and designed to 5 print a row of characters.

In shoe factories and the like where it is desired to print a row of characters to designate sizes, lot numbers, style numbers, etc., and in which the quantities of any one particular size or style are relatively small, it is common to provide machines which have interchangeable markers or type pieces so that the row of characters may be quickly varied in changing from one lot of work to the next. 10 Such machines of one type in extensive use have a moving head carrying a plurality of disks with markers upon their outer peripheries and are so arranged that the disks may be rotated upon the printing head to bring 15 the desired row of characters into printing position. For this purpose operator-controlled mechanism is usually provided of a type so designed that it is unnecessary for the operator to soil her hands or run the risk of 20 burning her fingers, in case the markers are heated, in bringing into position the desired characters. It will be understood, however, that in such machines the movable printing head is necessarily heavy because it carries all 25 the available type regardless of how little or how much of it is in actual use at the time and the movement of an unnecessarily heavy part is always productive of undue wear, vibration and the like. 30

In view of this fact, it is an object of the present invention to devise an improved marking machine so organized that it is only necessary to carry the particular types which are to be used for printing a piece of work, to 35 and from the type-carrying head to the work to be printed.

Accordingly, an important feature of the invention resides in a novel organization of type-carrying holders, type pieces detachably mounted on the holders, and a carrier for transferring a selected line of type pieces from the holders to printing position. In the illustrated arrangement the type holders are rotatably mounted upon a support, means being provided to rotate any desired type hold-

ers in order to choose the particular type pieces desired for making up the line of characters to be printed, and a carrier is so associated with the type holders that the rotation of the latter to bring the desired pieces of type into alignment operates to insert these pieces in the reciprocating carrier which is reciprocated to carry them to marking position.

Other features of the invention reside in a novel interlocking arrangement of individually removable type pieces with one another, with the holders, and with the adjacent parts of the type-carrying head. To this end each of the removable type pieces is provided on its lateral faces with a groove and a rib curved about the center of the type-carrying support, and one of the lateral faces of each of the type holder disks is also grooved to cooperate with the ribs on the removable type pieces. The relative construction and arrangement of these parts is such that none of the type pieces may be removed from the type-carrying head unless all the pieces of the line of characters are in alignment and only that row of type pieces which is to be carried to printing position may be removed from the holder, the other type pieces being securely held against accidental removal.

Still other features of the invention reside in auxiliary retaining devices employed upon the reciprocable type carrier. These and still other features are described in the following specification and illustrated in the accompanying drawings, in which:

Fig. 1 is a side elevation, partly in section, of the machine;

Fig. 2 is a front elevation, partly in section, of the machine;

Fig. 3 is a perspective view of the type holders and selecting mechanism;

Fig. 4 is a perspective view of the reciprocable carrier;

Fig. 5 is an exploded view of the type holders, their support, and the selecting mechanism co-operating with said holders;

Fig. 6 is a section through the type holder support showing one of the type holders in side elevation; and

Fig. 7 is a section upon the line VII—VII of Fig. 6.

In order to facilitate the selection of the desired type pieces to be used for any particular printing operation, the illustrated machine is provided with a support 10 comprising a cylindrical member rigidly positioned upon the frame 12 of the machine and held thereon by means of end brackets or retaining members 14 and 16 attached to projecting parts of said frame. A plurality of type holders 18 in the form of toothed disks are mounted side by side upon the support 10 and type pieces 20 are carried in the intervening recesses formed between the teeth of said disks. In accordance with the usual custom, these type pieces may be provided with characters arranged in order around the disks, as, for example, the digits one to nine and zero, or a series of letters of the alphabet or other characters as may be desired.

Selecting mechanism arranged to co-operate with the type holders comprises a pinion 22 arranged to mesh with gear teeth 24 formed upon the internal peripheries of the type holders 18 and adapted to be moved longitudinally of the cylindrical support 10 to bring said pinion into mesh with the teeth of any one of the type holder disks 18. To this end the pinion 22 is mounted upon a slender shaft 26 carried in blocks 28 (Fig. 5) joined by a projecting backing plate 30. The support 10 is suitably grooved at 32 to receive the blocks 28 and the groove is enlarged at 34 to receive the backing plate 30. Operating knob-like handles 36 (Fig. 3) are provided upon the ends of shaft 26 and the blocks 28 have thin ribs 38 just as wide as one of the teeth of the pinion 22 and in alignment therewith. A spring-pressed latch pin 37 (Fig. 2) helps to retain the handles 36 in positions corresponding to operative positions of the disks 18. It will be understood that the number of teeth 24 must bear a predetermined relation to the number of notches upon the outer periphery of the type holder 18 so that no matter what type is brought into position during the selecting operation, it will always be possible to reciprocate the pinion 22 along the grooves between the internal teeth 24. In other words, the process of selection must always bring one of the teeth of the pinion 22 into alignment with the retaining ribs 38. These ribs 38 will, therefore, be received between the teeth 24 upon the internal peripheries of the type holders and lock against rotation all but one of the holders as the selecting mechanism is moved along from one type holder to the next. In order to assist the operation of positioning the selecting mechanism, notches are provided upon the forward faces of the ribs 38 which co-operate with one or more spring-pressed latch pins 40 (Fig. 3) mounted in recesses in the end brackets 14

and 16 and held therein by threaded plugs 41.

If it is desired for the particular work to which the machine is to be applied, special type holders 42 and 44 may be provided carrying types so arranged that these holders may be adjusted individually and apart from the adjustment of the other holders by means of a handle 46 projecting from holder 44 to cause these holders to be changed step by step to indicate a series of sizes and half sizes. The arrangement of these particular holders is in accordance with the principle described in United States Letters Patent No. 984,588, granted Feb. 21, 1911, on the application of F. W. Merrick. In order that they may be adjusted independently of the other type holders and not subject to the retaining action of the ribs 38 upon the selecting mechanism, these particular holders 42 and 44 are supported upon a raised rib 50 formed upon the support 10, said support being provided with an internally disposed spring-pressed latch 52 (Fig. 6) co-operating with the internal periphery of the holder 42 to retain it in adjusted position. Attached to one side of the holder 42 is a notched ring 54 which serves as a support for the internal periphery of the holder 44 and in which the notches are arranged for engagement by a pawl 56 carried in said holder when the latter is moved in one direction. When the holder 44 is moved in the other direction, the pawl 56 and its co-operating notches are so disposed that the pawl slides over the ring 54 into position for engagement with the next notch.

The removable type pieces are provided with body portions having parallel lateral surfaces, as shown in Fig. 5, the narrower surfaces being spaced to fit the notches of the type holders 18, while on the broader lateral surfaces of the body portions of the type pieces curved grooves 60 and corresponding projecting curved ribs 62 are provided. Grooves 64 (Fig. 5) are also provided in one lateral face of each of the several type holders 18, the special type holder disks 42 and 44 and at 66 in the end bracket 14. On the inner face of the other end bracket 16 is provided a curved rib (indicated in dotted lines in Fig. 11) adapted to be received within the grooves 60 of the type pieces and the groove 64 of the endmost type holder adjacent to said end bracket. Thus the various type pieces in any particular line are interlocked with one another and with the end brackets 14 and 16 so as to prevent displacement thereof. In addition, whenever the type pieces are temporarily out of line during the action of rotating any particular type holder to select a character, then the type pieces are interlocked also with the adjacent type holder. It will also be seen that the construction described provides an arrangement of rotatable type holders carrying removable type pieces which are readily separable from

the particular holder by means of which they are supported and which may be moved circumferentially to bring them into alinement with other type pieces, but which are held 5 against accidental removal by reason of their engagement with adjacent type pieces or with adjacent type holders, or the end brackets 14 or 16.

The particular row of type pieces which 10 is selected for removal is positioned directly below the center of the support 10. To facilitate the process of selection, the type holders may, if desired, be marked on the end of their teeth, as indicated in Fig. 5, at a convenient fixed position about one-third of the 15 way around from the position in the holder occupied by the corresponding type piece so that the operator, in a manner well understood in the art, may readily determine which of 20 the type pieces are in position for removal at the bottoms of the holders.

A reciprocable carrier 70 comprises a relatively light frame made up of a cross piece and two end pieces 72 and 74. The end pieces 25 have upwardly extending projections 76 and 78 formed thereon, which are adapted to be received in corresponding recesses in the interrupted end retaining members 14 and 16. As shown in Figs. 1 and 7, the projection 76 30 is provided with a groove 80 adapted to receive the curved ribs 62 of the adjacent type pieces, while projection 78 has a curved rib 82 adapted to be received in the corresponding grooves 60 of the type pieces which are 35 adjacent thereto. When, therefore, the type carrier is in type-receiving relation, the process of selection, during which various holders are rotated to bring particular type pieces into alinement at the bottom of the 40 support, serves also to insert these selected type pieces directly in the carrier ready for removal and transfer to printing position and conversely, after the printing operation has been finished, the return of the type carrier 45 70 to its upper position places the type pieces which have been used directly back in the notches of their respective holders in the positions which they previously occupied so that, in the subsequent process of selection, 50 rotation of a holder removes any of the desired type pieces from the carrier 70 and inserts another type piece in its place.

Although the various type pieces of the particular row being used for printing are 55 interlocked with one another against vertical displacement and with the reciprocating carrier 70 by means of their coating ribs and grooves, it may be desirable to prevent accidental lateral displacement, and to this end 60 a displaceable hollow frame 84 is pivotally mounted on the carrier 70 and is resiliently held by springs 86 in a position determined by notches 88 on the under sides of the end pieces 72 and 74 of the carrier. This frame 65 84 is provided with a slot 90 having tapered

sides (see Fig. 1) to co-operate with the tapered ends 92 of the outwardly projecting parts of the body portions of the removable type pieces 20 so that it is essentially a pair of bars with supporting means to hold them in parallel spaced relation, and it is intended to be moved aside during the selection of these type pieces and then brought into position so that the tapered ends 92 are received in the slot 90 of the displaceable frame 84 70

as the carrier is moved into and out of printing position, thereby to prevent lateral displacement of the various type pieces. In order that this frame may readily be moved aside during the process of selection, an 75 arm 94 is provided upon its pivot outside the end member 72 of the carrier in position for engagement with one arm of a bell crank lever 96, which is operator-controlled as by means of a treadle rod 98 (Fig. 3). Further 80 assurance against accidental displacement of the type pieces in the row carried by the reciprocable carrier 70 is provided in the form of a clamp screw 100 by means of which any 85 looseness, resulting from imperfect construction of the various type pieces or wear there- 90 of after use, may be taken up as the carrier is moved into printing position and the type pieces thus clamped rigidly together to form substantially one compact mass during the 95 printing operation. Preferably, means are provided for operating this screw in conjunc- 100 tion with the operation of the displaceable frame 84 so that the displacement of the frame results in a release of the clamp screw. 105

For this purpose an arm 102 may be provided upon the clamp screw co-operating with an arm 104 mounted upon the arm 94. If, as is frequently the case, more than one 110 row of characters is to be printed at a single operation, in order to apply style names, trade-marks and the like which do not have frequently to be changed as the operator goes from one group of work to another, then special type pieces 106 (Fig. 4) may be 115 provided which are grooved for frictional engagement with the edges of the hollow frame 84, as illustrated in Fig. 1, and having once been mounted on said frame are left thereon during a substantial period of time. If it 120 is desired to heat the characters upon the type-carrying support, then the support 10 may be recessed at 108 to receive an electric cartridge heating unit.

The type holder support 10 is, as previously described, supported by means of end brackets 14 and 16 upon the frame 12 having forwardly projecting bearing members in which are mounted for vertical reciproca- 125 tion rods 112 (Fig. 3) rigidly attached to the carrier 70. To provide for the reciprocation of this carrier and the operation of other parts of the machine, a power shaft 114 (Fig. 2) is mounted in the frame 12 and is pro- 130 vided with a driving pulley 116 loosely

mounted thereon and adapted to be pressed into driving engagement with a clutch cone 118 by means of a spring 120 received between a cap 122 bearing against the end of the hub of the driving pulley 116 and an outer cap 124 screwed to the end of the shaft 114. It will be observed that the clutch cone 118 is pinned to the shaft and that its hub serves as a bearing for oppositely disposed operating pins 126 bearing at their outer ends 10 against a plate 128 resting against the hub of the driving pulley 116 and at their inner ends against a grooved collar 130 loosely mounted on the driving shaft. When no pressure is exerted upon the collar 130, the 15 action of the spring 120 presses the driving pulley 116 into engagement with the clutch cone 118 and rotates the drive shaft 114. When, however, it is desired to stop the machine, the grooved collar 130 may be 20 moved to the right, as in Fig. 2, by means of a forked lever 132 which is, together with another lever 134, (Fig. 1) pivotally mounted upon a pin 136 carried between lugs 138 and 140 formed upon the machine frame. The 25 lever 134 is provided with a cam roll 142 bearing against a face cam 144 mounted upon a cam shaft 146 (Fig. 1), which is pivoted in the frame of the machine. This cam, which is provided with a single projection 148 (Fig. 30 2), is arranged to lift the cam roll 142 and its supporting lever 134 at the end of a complete operation of the machine, the roll being held against the cam by means of a spring 150 inserted in a pocket formed in the frame 35 and bearing against a lug 152 formed integrally with the hub of the lever 134. Operator-controlled connecting means are then provided to interconnect the levers 132 and 134 so arranged that when said levers are 40 connected, the lifting of the lever 134 by the projection 148 on the cam 144 serves also to push the grooved collar 130 to the right and thereby to disengage the clutch cone 118 from the driving pulley. This operator-controlled 45 connection comprises a squared pin 154 (Fig. 2) extending to the right from the lever 132 and adapted to be engaged by the notch of a latch 156 pivotally mounted at 158 at the lower end of the lever 134. The latch 156 is 50 also provided with an arm 160 disposed upon the other side of the lever 134 and arranged substantially parallel thereto, said arm at its outer end being connected to the upper 55 end of a treadle rod 162 which is spring-pressed upwardly by means of a spring 164 to hold the latch in engagement with the squared pin 154 but may be depressed to start the machine or to cause a continuing 60 operation thereof by pulling down upon the treadle rod 162. A guide lug 166 for the treadle rod is provided upon the frame of the machine.

Prior to the reciprocation of the type carrier 70 to imprint the work, ink is supplied

to the row of type pieces in the carrier. To this end a vertically disposed, ink-carrying plate 170 is mounted at the center of the cross bar at the front of a rectangular frame 172, the other end of which is pivotally supported by means of cone-shaped screws one of which is shown at 174 in Fig. 1. The nearer side arm 176 of this rectangular supporting frame, as viewed in Fig. 1, is provided with a forked portion 178 engaging and surrounding an eccentric 180 which, preferably, is formed integrally and upon the back side of a gear 182 upon the cam shaft 146, this gear meshing with a pinion 184 upon the drive shaft. The ink plate 170 is supported upon this frame 172 by means of a headed stud 186 which passes through an opening in the cross bar of the frame 172 and is surrounded by a spring tending to hold the plate forwardly, such forward movement being limited by the head of the stud 186. In order to transfer the ink from this plate 170 to the type, a roll 190 is pivotally supported in the outer ends of short arms 192 which are carried at the lower end of depending arms 194 formed integrally with a cross rod 196 (Fig. 2) which is pivotally supported between forwardly extending lugs upon the frame 12 of the machine by means of conical screws 198. As is shown in Fig. 1, springs 200 are interposed between the arms 192 and the arms 194 tending to hold the former upwardly to press the roll 190 into contact with the type. It is noted that the roll 190 is received in U-shaped slots at the outer ends of the arms 192 to facilitate its ready removal for cleaning or the like. Passage of the inking roll over the row of type pieces which is to be carried into printing position is facilitated by means of guide members 202 secured to the outside of the end brackets 14 and 16 with the lower surfaces of these guide members 202 in the plane of the raised printing surfaces upon the type pieces. Hooked ends 204 are provided upon the rear ends of each of the guide members 202 to hold the inking roll 190 rigidly in position when the latter is in inoperative position in engagement with the inking plate 170 so that the vertical oscillation of the latter is effective to rotate the inking roll 190 and thoroughly to distribute the ink on said roll as the inking plate 170 is moved up and down by means of the eccentric 180. Movement of the depending supporting arms 194 for the inking roll is effected through a link 206 (Fig. 1) connecting one of said arms to the upper end of a bell crank 208, the lower end of which is provided with a cam roll engaging a cam slot formed at the end of a cylindrical cam member 210 (Fig. 1), which is supported upon the cam shaft 146 between the side arms of the rectangular frame 172 supporting the inking plate.

To reciprocate the type carrier 70 from the type holders into contact with the work and

back again to the type holders a block 212 is mounted upon the vertical rods 112 and provided with a transverse slot to receive a block 214 pivotally supported upon a circular plate 216 which is mounted upon a shaft 218 supported in the frame of the machine. This shaft 218 is provided with a gear 220 meshing with the teeth of a segment 222 formed at the upper end of a lever 224 having a cam roll 226 (Fig. 1) received within a cam slot formed in the periphery of the cylindrical cam member 210. This lever 224 is pivoted between pointed screws 227 (Fig. 1) in the frame of the machine and is provided with a downward extension 228 (Fig. 2) for co-operation with mechanism controlling the work-supporting table 230.

The work-supporting table 230 is mounted at the upper end of a hollow post 232 which is slidably received within a socket of a bracket 234 attached to the frame of the machine. A spring 236, the tension of which is adjustable by means of a screw 238, is interposed between the bottom of the socket and the table post 232 tending to hold the work and the table resiliently in contact with the type when an impression is made. At other times the table is locked against upward movement by means of a key 240 held in a recess of the table post 232 and locked by an eccentric portion 242 of a horizontal rod 244. Upon the rear end of this rod a short arm 246 is provided which is in the path of a bolt 248 at the lower end of the extension 228 of the operating lever 224. A spring 250 imposed between the frame of the machine and this arm 246 normally holds the eccentric portion 242 of the rod 244 in position to lock the table against vertical movement. When the operating lever moves to reciprocate the carrier, however, the lower end of the lever is effective to release this locking device by bearing against the arm 246 as soon as the type pieces have come in contact with the work upon the table and the table is again locked as soon as, or just before, the type pieces are moved out of contact with the work. Thus the character of the impression is rendered independent of the number of pieces, or the thickness of the pieces of work, upon the table.

In using the machine, the operator will first depress the treadle rod 98 (Fig. 3) to release the clamping screw 100 and to depress the hollow frame 84 away from the type. The selecting mechanism may then be operated by means of the knob handles 36 or the size lever handle 46 to bring the desired characters into position in the carrier 70. This accomplished, the treadle rod 98 will be released to cause the sides of the opening 90 in the hollow frame 84 to aline the type pieces in the carrier, and at the same time to cause the clamp screw to be tightened so that these type pieces are substantially one continuous mem-

ber, it being understood that they are interlocked with one another and with the carrier by reason of the rib and groove construction already described. The clutch treadle rod 162 will then be operated to supply power to the drive shaft 114 by means of which the inking roll will be oscillated over the type pieces and the type carrier 70 reciprocated to bring the type into contact with the work to make an impression. If the operator releases the clutch treadle rod 162 as soon as the machine has started, then only a single impression will be made and the machine will stop. If, however, it is desired to make several impressions of the set-up of type, continuous action of the machine is afforded by maintained depression of the treadle rod 162.

Having described the invention, what I claim as new and desire to secure by Letters Patent of the United States is:

1. In a marking machine, a support, a plurality of separable type pieces on said support, a work support, a carrier, and means moving with the carrier for gripping firmly the ends of and removing a line of type pieces from the support and impressing them on a piece of work placed upon the work support.

2. In a marking machine, a support for a plurality of separable type pieces, constructed and arranged to lock most of the type pieces against removal and to release only certain pieces which are arranged side by side to form a line, a work support, and a carrier arranged to move a line of type pieces away from the support, press them on a piece of work placed on the work support and then return them to the position from which they were taken.

3. In a marking machine, a support, a plurality of type holders movably mounted upon said support, separable type pieces in said holders contacting laterally with one another to form lines, means for selectively actuating said holders to bring the desired type pieces into alinement, and a carrier arranged to interlock with the end pieces of a line of type selected from various holders and to remove said line of type pieces and impress it on the work.

4. In a marking machine, a support, holders rotatably mounted upon said support, removable type pieces, detachably carried in said holders and arranged to be interlocked with adjacent type pieces in other holders to form a row means for selectively actuating said holders to bring into line the desired pieces with which to imprint the work, and means for retaining in the holders the type pieces which are not to be used to imprint the work.

5. In a marking machine, a support, recessed holders movably mounted upon said support for adjustment in parallel planes, and removable type pieces carried in the recesses of said holders and adapted to be

brought into alinement, said type pieces being interlocked with an adjacent holder when out of alinement with the type pieces thereof.

6. In a marking machine, a support, recessed holders adjustably mounted upon said support, and removable type pieces carried in the recesses of said holders, said type pieces being interlocked with adjacent type pieces in other holders when the type pieces of the various holders are alined and being interlocked with an adjacent holder when out of alinement with the type pieces in said holder.

7. In a marking machine, a type holder provided with a plurality of projecting teeth forming intervening recesses, and type pieces detachably mounted in said recesses, said type pieces and the teeth being provided with grooves in alinement with one another.

8. In a marking machine, a type holder provided with a plurality of projecting teeth forming intervening recesses, type pieces removably mounted in said recesses, said type pieces and the teeth being provided with grooves in alinement with one another, and a ribbed member arranged to co-operate with the grooves in a plurality of the type pieces in said holder.

9. In a marking machine, a type holder provided with a plurality of projecting teeth forming intervening recesses, type pieces detachably mounted in said recesses, said type pieces being provided with lateral projecting ribs, and a grooved member arranged to co-operate with the ribs of all but one of the type pieces in said holder.

10. In a marking machine, a support, a disk-shaped type holder rotatably mounted upon said support and having projecting teeth at its outer periphery forming intervening recesses, removable type pieces carried in the recesses of said type holder, means for holding all but one of the type pieces in the holder, and means arranged for engagement with the inner periphery of the type holder to rotate the type holder upon the support.

11. In a marking machine, a support, a plurality of disk-shaped type holders rotatably mounted upon said support, a series of removable type pieces carried in said holders for movement therewith as the holders are rotated, means for locking a predetermined fractional part of the pieces carried by any particular holder in the holder, and selecting means for turning the holders to bring the desired piece of type in any particular holder into a predetermined position where it is not locked, for removal from the holder.

12. In a marking machine, a support, a type holder movably mounted upon said support, removable type pieces carried in said holder, locking means on said support arranged to engage all but one of the type pieces in said holder, a movable carrier, and means upon said carrier arranged to have locking engage-

ment with the remaining type piece in said holder.

13. In a marking machine, a movable carrier, a row of separable type pieces supported by said carrier, and means mounted for movement relatively to the carrier constructed and arranged to engage the opposite edges of the row of type pieces to aline them and to prevent displacement of said type pieces out of alinement with adjacent type pieces, said means and said type pieces having coacting beveled surfaces to assist in alining the type pieces.

14. In a marking machine, a row of separable type pieces constructed and arranged to interlock with one another, a movable carrier constructed and arranged to support said row of type, the carrier and the end pieces of the row being constructed and arranged to be interlocked, and means upon the carrier to prevent lateral displacement of any of the type pieces out of alinement with the row of adjacent pieces.

15. In a marking machine, a supply of type pieces arranged in order, a movable carrier constructed and arranged to receive and support a row of removable type pieces taken from said supply and provided with interlocking ribs and grooves on their lateral contacting faces, means to aline said row of type pieces on the carrier, and means upon said carrier for pressing together the single row of separate type pieces in interlocking relation.

16. In a marking machine, a plurality of movable holders provided with a series of removable type pieces for selection, and a type carrier movably mounted with respect to said holders constructed and arranged in one position to support a changing row of type pieces during the selective movement of the holders and to receive said row of type for removal from the holders as said holders are adjusted to bring selected characters into alinement.

17. In a marking machine, a support, a plurality of type holders movably mounted side by side upon the support, removable type pieces carried by said holders and capable of being positioned in rows transversely of the holders while still therein with the component pieces of each row in contact with adjacent pieces thereof, means for preventing the accidental removal of a plurality of the transverse rows of type, and a carrier arranged to receive and hold in alinement one row of type from the holders.

18. In a marking machine, a support, a plurality of type holders movably mounted side by side upon the support, removable type pieces carried by said holders and capable of being positioned in rows transversely of the holders while still therein with the component pieces of each row in contact with adjacent pieces thereof, means for preventing

- the accidental removal of a plurality of the transverse rows of type, and a carrier arranged to receive one row of type from the holders and to grip it to prevent accidental displacement of the pieces from the row.
- 5 19. In a marking machine, a support, a plurality of type holders movably mounted side by side upon the support, removable type carried by said holders and capable of being positioned in rows transversely of the holders while still therein with the component pieces of each row in contact with adjacent pieces thereof, means for preventing the accidental removal of a plurality of the transverse rows 10 of type, and a carrier arranged to receive one row of type from the holders, transfer it into marking position and return it in position for re-engagement with the holders.
- 10 20. In a marking machine, a plurality of type holders movably mounted side by side, removable type carried by said holders provided with interlocking projections and recesses and end members provided with corresponding projections and recesses to prevent 15 the accidental removal of a plurality of rows of type, said end pieces being broken away to permit the removal of one row of selected type.
- 20 21. In a marking machine, a support, type holders movably mounted on said support, individual type pieces carried by said holders, said type pieces and said support being provided with interlocking means to prevent the accidental removal of a plurality of rows of 25 type, a movable carrier provided with co-operating locking means arranged to engage one of the rows of type, and a displaceable frame upon said carrier arranged to be moved aside to allow the selection of the desired line 30 of type and arranged to be brought into position adjacent the selected line of type when the carrier is moved away from the type holders to carry said line of type into printing contact with the work.
- 25 22. In a marking machine, a support, a plurality of holders having teeth and intervening notches movably mounted on said support, type pieces removably mounted in said holders having ribs and grooves on their 35 lateral faces, the lateral faces of the teeth at one side of the type holders having grooves to receive the ribs on the adjacent set of type pieces as any particular holder is moved to select the type character desired.
- 50 23. In a marking machine, a plurality of holders provided with a series of removable type pieces, a type carrier movably mounted with respect to said holders, and means for adjusting said holders to place selected type 40 pieces in the carrier and to remove other type pieces from the carrier.
- 55 24. In a marking machine, a support, a holder movably mounted upon said support arranged to support a plurality of removable type pieces, said support being provided with 45 an interrupted retaining member constructed and arranged to cooperate with a plurality of the type pieces in said holder, and a movable carrier having a retaining member interposed in the interruption of the retaining member upon the support.
- 50 25. In a marking machine, a support, a plurality of holders adjustably mounted on said support and provided with series of removable type pieces, a type piece carrier, and selecting mechanism constructed and arranged to adjust said holders to select individual type pieces from the various holders and as an incident to the selecting movement to bring said type pieces into position in the carrier.
- 55 26. In a marking machine, a support, a plurality of holders rotatably mounted on said support and provided with series of removable type pieces, selecting mechanism constructed and arranged to bring individual type pieces from the various holders into position at the bottoms of the holders, and a carrier for the selected type pieces constructed and arranged to receive said pieces as they are brought to the aforesaid position.
- 60 27. In a marking machine, a plurality of selective holders, removable type pieces carried in rows in said holders provided with locking means arranged to co-operate with adjacent holders when out of alinement with the type carried by said adjacent holders and with the type in said holders when in alinement therewith, and end retaining members constructed and arranged to hold all but one row of type.
- 65 28. In a marking machine, a plurality of type pieces having tapered body portions, means for supporting a row of said type by engagement with the end members of said row, and a hollow frame constructed and arranged to aline the type pieces in a row by engagement with the tapered body portions.
- 70 29. In a marking machine, a plurality of type pieces, means for supporting a row of said type by engagement with the end members of said row, a hollow frame constructed and arranged to aline the type pieces in the row, and means for clamping said alined type pieces.
- 75 30. In testimony whereof I have signed my name to this specification.
